UNITED STATES PATENT OFFICE.

PHILEMON O. DICKINSON, OF NEWARK, NEW JERSEY.

DESIGN FOR A POCKET-BOOK, &c.

SPECIFICATION forming part of Design No. 25,600, dated June 9, 1896.

Application filed April 30, 1896. Serial No. 589,784. Term of patent 31 years.

To all whom it may concern:

Be it known that I, PHILEMON O. DICKINSON, a citizen of the United States, residing at Newark, in the county of Essex and State 5 of New Jersey, have invented and produced a new and original Design for Pocket-Books and Similar Articles, of which the following is a specification, reference being had to the accompanying drawings, which illustrate the 10 design.

The present design relates to a corner border in metal to be applied to the edges of a corner of a flap or other part of a pocket-book or similar article.

15 In the drawings, Figure 1 represents a face or plan view of the design. Fig. 2 represents a detail cross-section on *a a* of Fig. 1 of the metal bearing the design and which incloses the corner edge parts of the flap or other part 20 of the pocket-book or similar article.

Referring to the design in detail, the same consists in essential style of the roccoco pattern arranged in elements as follows: A and

B are parts of the design extending border-like along the edge of the flap or other part 25 and running together in rounded outline form at the corner C, where occurs the rosette or disk-design part D. The border B is composed, together with the center part D, of the two design groups E and F, while 30 the border A is composed, together with the center part D, of the one group part G.

In Fig. 2 the cross-section shows the flap II, which is bent around the edge of the material to which the design metal is secured 35 and for the purpose of securing such metal to the material.

What is claimed as new is—

The herein design for pocket-books and similar articles, substantially as shown and 40 described.

PHILEMON O. DICKINSON,
